UNITED STATES PATENT OFFICE.

RICHARD J. BEALL, JR., OF WASHINGTON, DISTRICT OF COLUMBIA.

PROCESS OF FORMING CONCRETE PILES.

No. 903,126.

Specification of Letters Patent.

Patented Nov. 3, 1908.

Application filed April 16, 1904, Serial No. 203,492. Renewed June 20, 1908. Serial No. 439,594.

To all whom it may concern:

Be it known that I, RICHARD J. BEALL, JR., a citizen of the United States, residing in the city of Washington, District of Columbia, have invented certain Improvements in the Process of Forming Concrete Piles, of which the following is a specification.

My invention relates to that method of forming piles of concrete or cement which 10 consists in first driving a preparatory pile into the ground, then withdrawing said preparatory pile, and then filling the opening formed thereby with concrete or cement in fluid or plastic form, which when it becomes 15 set forms the permanent pile.

The object of my invention is to provide for driving or withdrawing the preparatory pile with the exercise of much less power than is required when piles of this class as 20 heretofore constructed are used.

In the accompanying drawing: Figure 1 is a sectional view illustrating the method of forming the opening in the ground by means of the preparatory pile in accordance 25 with my invention, and Fig. 2 is a similar view showing the preparatory pile removed and the opening filled with concrete to form the permanent pile.

For the purpose of forming in the ground 30 openings for the reception of concrete or cement to constitute a permanent pile the use of an ordinary wooden or metal preparatory pile of cylindrical form or tapering inwardly from top to bottom is objectionable, for the reason that the frictional hold of the earth upon the sides of the same is such that the pile cannot be driven beyond a limited distance without the exercise of destructive force and cannot be withdrawn 35 after being driven without the exercise of still greater force, frictional hold of the earth upon the pile being now assisted by atmospheric pressure owing to the fact that the withdrawal of the pile tends to create a partial vacuum in the opening left thereby. For 40 this reason various forms of collapsible piles have been proposed; but such piles, owing to their sectional character, are necessarily limited in strength and, moreover, do not 45 overcome the objection of resistance to the frictional hold of the earth thereupon while they are being driven. When the pile tapers inwardly from top to bottom, there is the same resistance to the driving of the pile, 50 and the resistance to the withdrawal of the pile is also excessive, because owing to the

atmospheric pressure the earth is caused to cling firmly to the pile, so as to increase the difficulty of starting the pile and retard its movement for some time after it is started. 60 In carrying out my invention, therefore, I displace the earth at and near the point of the preparatory pile to a greater extent than the diameter of said pile, thereby freeing the pile, except as to a limited area at and near 65 the point from any material frictional contact with the walls of the opening formed thereby, thus not only facilitating the driving of the pile, but also the withdrawal of the same. Such withdrawal is further fa- 70 cilitated by permitting an inflow of air into the space below the pile as said pile is withdrawn from the opening, thus preventing the frictional grip due to atmospheric pressure and this feature of my invention may be 75 adopted even in connection with the ordinary preparatory pile, which it not furnished with the enlarged point, since such provision materially lessens the difficulty of withdrawing 80 said preparatory pile from the opening formed thereby.

On reference to Fig. 1 it will be observed that the preparatory pile 1 is in the form of a metal tube, although it may be a solid pile of wood or metal, if desired, 85 this pile being provided at the top with a suitable driving-head 2 and at the bottom with a point 3, which is of so much greater diameter than the pile 1 that there is no likelihood of the latter coming in contact 90 to any material extent with the walls of the opening formed by driving the pile. The point is reduced in diameter at the top, so as to provide a shoulder for engagement with the lower end of the pile, 95 and this reduced portion of the point may, if desired, be secured to the lower end of the pile by rivets 4 or other suitable fastenings, or the pile and its point may be in one piece, if desired. The point 3 has 100 a tapered lower end, and also, by preference, tapers from its portion of greatest diameter inwardly to the shoulder, upon which rests the lower end of the pile 1, so that no abrupt shoulders are presented to the earth 105 either in driving the pile or withdrawing the point. The point 3 is hollow and has an opening therein, which during the driving of the pile may be closed at the lower end by a valve opening downwardly, this 110 valve in the present instance consisting of a detachable plug 5, which will be released

as soon as the withdrawal of the pile is attempted, so as to permit of a downward passage of air through the pile and point, thus preventing the formation of a partial 5 vacuum in the opening below the point of the pile, and thereby relieving said point from any frictional hold of the walls of the opening thereupon due to atmospheric pressure. Of course it will be understood 10 that in withdrawing the pile that the driving-head 2 is removed, or other means are provided for permitting free ingress of air to the interior of the pile. After the preparatory pile has been withdrawn the opening 15 is filled with concrete or cement and the latter is permitted to remain without disturbance until it becomes set, so as to form the permanent pile 6, as shown in Fig. 2.

20 Having thus described my invention, what I claim and desire to secure by Letters-Patent, is:—

1. The method of making concrete piles which consists in providing a pile with an opening therethrough, driving said pile to displace the earth, then withdrawing the pile and permitting a flow of air through the same into the hole below the pile, then filling the hole thus formed with concrete 30 and permitting the same to set, substantially as specified.

2. The method of making concrete piles which consists in providing a pile with an enlarged head and an opening therethrough, driving said pile to displace the earth, and thereby form a hole larger than the pile-stem, withdrawing the pile and permitting a flow of air through the same into the hole beneath the pile, and then filling the hole 40 thus formed with concrete and permitting the same to set, substantially as specified.

3. The method of making concrete piles which consists in providing the pile with an opening therethrough having a detachable

closure at the point of the pile, driving said 45 pile to displace the earth, withdrawing the pile, without said closure, and permitting a flow of air through the pile into the hole below the same, and then filling the hole thus formed with concrete and permitting 50 the same to set, substantially as specified.

4. The method of making concrete piles which consists in providing the pile with an enlarged head and an opening therethrough having a detachable closure at the 55 point of the pile, driving said pile to displace the earth and thereby forming a hole larger than the pile-stem, withdrawing the pile, without the closure, thereby permitting a flow of air through the pile into the 60 hole beneath the same, and then filling the hole thus formed with concrete and permitting the same to set, substantially as specified.

5. The method of making concrete piles 65 which consists in providing a pile with an enlarged head, driving said pile to displace the earth and thereby forming a hole larger than the pile-stem, withdrawing the pile, and afterward filling the hole with concrete, 70 substantially as specified.

6. The method of making concrete piles which consists in providing a pile with an enlarged head, driving said pile to displace the earth, and thereby forming a hole larger 75 than the pile-stem, withdrawing the pile, filling the hole with concrete, and permitting said concrete to remain without disturbance until it becomes set, substantially as specified.

In testimony whereof I have signed my name to this specification in the presence of two subscribing witnesses.
